IGNITION SYSTEM FOR CASELESS ROUNDS IN
OPEN BREECH TYPE GUNSThomas Stevenson, 1039 Arthur Ave.,
Huntingdon Valley, Pa.

Filed Nov. 18, 1958, Ser. No. 774,790

5 Claims. (Cl. 89—1.7)

(Granted under Title 35, U.S. Code (1952), sec. 266)

The invention described herein may be manufactured and used by or for the Government for governmental purposes without the payment to me of any royalty thereon.

This invention relates to the firing of caseless rounds in open breech type guns and has for an object to provide a new and simple percussion system for firing such a weapon to eliminate the need for the presently used electrical or other connections entering the breech opening. Another object has been to provide a greater approach to uniformity in firing such rounds under widely different ambient temperatures. Yet a further object is to enable a hotter igniter flame to be available for such ammunition than has been standard practice.

In firing open breech type guns with caseless ammunition considerable objection has been voiced to the presence of electrical connections or a steel cable or a powder fuse transmission line entering the breech for firing the charge because such connections must be attached in the field and get in the way of gunners, require connection in all kinds of weather and require a quick disconnection on firing. Yet no satisfactory solution has appeared.

According to this invention such connections have been eliminated with elimination of their attendant objections.

A serious objection to the use of open breech guns with caseless ammunition has been the serious effect wide temperature variations are found to have in the burning of such ammunition with corresponding variations in pressure and effective range. It is not feasible to transport many or even a few different types of caseless rounds, one for a particular temperature range and another for a different range of ambient temperatures. Although it is known that different kinds of igniting flames produce different effects in the same kind of propelling charge and differences in the range, no one has heretofore realized the desirability of using selected igniting flames, especially in open breech guns with caseless ammunition to compensate for temperature changes and obtain a closer approach to uniformity in range under wide temperature variations.

Accordingly the present invention provides igniting flames of different temperatures and lengths to effect a closer approach to ballistic uniformity with more nearly constancy in range with open breech guns using caseless ammunition under different temperature conditions of the air. By caseless ammunition is usually meant a unit composed of a projectile and propelling charge in which an enclosing casing for propellant is either absent or easily combustible. More specifically under this invention blank cartridges can be selected for the field temperature conditions and fired by percussion after being positioned so that the flame enters a small hole in a side wall of the open breech gun to fire the propellant. The thin side wall of such a gun enables the igniter flame to pass through a small hole without an objectionable amount of heat of the flame being absorbed by the walls

2

of the hole. A caseless round permits an igniter flame to ignite the propellant through said hole.

This invention is adapted for use with projectiles of either the spin or fin stabilized sort. With fin stabilized projectiles it has an advantage by reason of the fact that with black powder enclosed by a central perforate boom connecting stabilizing fins and projectile and surrounded by propellant, there has been a limit to the temperature generated by an igniter flame when such boom is of aluminum. This is because high igniter temperatures would melt, destroy, or damage this boom. Under the present invention when an igniter flame does not have to pass through such boom there is less danger of that boom being raised to its kindling temperature with the igniter flame moving radially inwardly rather than outwardly. This invention is distinguished from the old muzzle loading weapon fired by a line of burning powder or a fuse through a touch hole. In that early weapon the flame reaching the propellant did not originate outside the gun but inside by the powder burning along a line extending through the wall of the gun. The origin of the burning powder line started outside but progressed inside as the line of black powder or fuse burned. Were an igniting flame to have been initiated only on the outside of the gun rather than to have a progressive origin, an excessive amount of heat would have been absorbed by the thick walls of the gun. With recoilless and open breech guns the side walls are much thinner for a gun of the same size, enabling them to be lighter in weight. The old muzzle loaded guns used separate loading ammunition and not caseless rounds as the term is defined herein.

The single figure of the drawing shows one embodiment of this invention in an open breech type gun containing a fin stabilized projectile.

Such a gun 10 has a projectile 11 therein provided with stabilizing fins 12 connected with the main body of the projectile by a boom 13 enclosed in a propelling charge 14 surrounded by a thin easily perforable plastic or preferably easily combustible container 15. With this method of ignition the boom need not be perforated nor contain black powder or other igniting material. Yieldable flaps 16 control recoil and are capable of retaining a projectile in the gun when elevated, to prevent the round from falling out of the gun by gravity.

Beneath the gun is shown some suitable form of magazine containing a number of blank cartridges 17 fed to the firing chamber 21 by a usual follower spring not shown. This magazine is supported at its left end by a threaded sleeve 18 engaging corresponding threads in the gun and this sleeve is provided with a generally axial hole 20, through which an igniting flame from the blank cartridge 17 is fired to ignite the propelling charge 14. To be rid of connections leading into the open breech each blank cartridge is fired by trigger 19 actuating some known form of mechanical impact or percussion device 23 within the enclosure shown and forming no novel element of this invention firing it as a flame source. The forward end of the blank cartridge magazine is supported from the gun 10 by a metal strap 22.

This invention is for use principally in recoilless guns of the open breech type having caseless ammunition which the igniting flame can readily penetrate and ignite the propeller charge 14. This invention was tried out in a 90 millimeter gun having a wall thickness of .157 inch. The hole for the initiator flame was $\frac{1}{8}$ of an inch in diameter.

An outstanding advantage of this invention is increased efficiency of ignition applied to a gun of the open breech type. Where loaded with a fin stabilized projectile since less than half as much initiator material is needed under

this invention as is needed when black powder fills a perforate boom as is customary under the prior practice.

Under this invention a weapon system including a gun 10 having a chamber for a propellant 14 is fired by a smaller or auxiliary weapon system including a magazine for cartridges 17, means for firing a cartridge, and means for directing a flame from the fired cartridge into said propellant chamber by a substantially straight line. The spaces occupied by propelling charge 14 and projectile main body portion are known as the propellant chamber and projectile chamber, respectively. Taking the dimensions given above, the inside diameter of the initiator flame passageway or tube is about 2.3879 times the gun wall thickness of .157 inch. This inside diameter of .375 inch is about .1057 times the bore diameter of the 90 millimeter gun. The term "solid propellant" does not mean that the caseless propellant 14 has to be in one block because usually a solid propellant is in particles which may be of various shapes and sizes.

I claim:

1. In an open breech type of recoilless gun having a chamber for reception of a caseless solid propellant in a rear portion of said gun, a second chamber for reception of a main body portion of a projectile in front of the first mentioned chamber, means for holding a round in said gun to prevent it from falling out by gravity when a muzzle of the gun has been elevated, and means for firing a caseless solid propellant in the first mentioned chamber of said gun, the combination therewith of the improvement in said firing means whereby the time consuming tedium of making electrical connections in all kinds of weather and firing a propellant through current supplied by said connections extending through an open breech may be eliminated, said firing means improvement including a substantially straight enclosed flame passageway directed laterally through a side wall of said gun and into said chamber for caseless propellant, means for positioning a blank cartridge in alinement with said passageway, a trigger operated percussion type firing mechanism for a cartridge positioned at said passageway, and a plurality of blank cartridges some of which are distinctively different by having different types of explosives in cartridge cases of the same diameter may be selectively presented to said passageway for directing initiator flames of different available temperatures to compensate for wide ranges of ambient temperature and whereby a faster rate of firing said recoilless gun is obtainable than is possible with the use of electrical connections entering through the open breech type of such guns.

2. A combination according to claim 1 in which blank cartridges are slideable as a unit in a magazine for positioning them one at a time in alinement with said enclosed passageway at an outer end thereof.

3. In an open breech type recoilless gun having a chamber for a caseless propellant in a rear portion of said gun, a projectile chamber in front of said propellant chamber, means for holding a round in said gun to prevent it from falling out of the gun by gravity when a muzzle of the gun has been elevated, said means comprising yieldable flaps the shape of which controls recoil, and means for firing propellant in said chamber, the

combination therewith of the improvement in said firing means whereby a more rapid rate of fire may be attained by elimination of the time consuming tedium of extending and fastening electrical connections in all kinds of weather through the open breech and then electrically firing a propellant in the gun, said improvement including a straight laterally directed threaded passageway for an igniter flame leading through a side wall of said gun into said propellant chamber, means for positioning a blank cartridge alined with said passageway and adjacent said gun, a trigger operated percussion type firing means for firing a blank cartridge when alined with said passageway, said passageway having an inside diameter larger than a side wall thickness for the gun.

15 4. A combination according to claim 3 in which said yieldable flaps engage stabilizing fins on a unitary caseless round when inserted in said gun and said round having propellant located around a boom extending between such fins and a main body portion of a projectile 20 whereby a saving of about 50% in initiator explosive for firing a propellant is available in a blank cartridge as compared with what had been used in said boom with the aforementioned electric igniter connection entering the open breech for firing an igniter in said boom.

25 5. In an open breech type recoilless gun having a chamber for a caseless solid propellant, a projectile chamber at least partially in front of said propellant chamber, means for holding a round in said gun to prevent it from falling out by gravity when a muzzle of the 30 gun is elevated, and means for firing said propellant in the gun, the combination therewith of the improvement in said firing means whereby the rate of fire may be increased and the time consuming tedium of making electrical connections in all kinds of weather for firing 35 propellant by current supplied through such connections may be eliminated, said improvement being in said firing means and including a straight flame passageway from adjacent the mouth of a cartridge case and with said passageway being directed laterally through a side wall 40 of said gun into said propellant chamber, an inside diameter of said passageway being larger than the wall thickness of said gun, means for positioning a cartridge case containing an explosive with the mouth of such a case at the outer end of said passageway and outside said 45 recoilless gun for directing a flame initially at least in a direction away from a cartridge case so positioned and through said passageway when fired for firing a caseless propelling charge in said gun, and a trigger operated percussion type firing means for a cartridge so positioned.
